Primary Examiner — Garth Rademaker*Assistant Examiner* — Melanie Pellegrini(74) *Attorney, Agent, or Firm* — Kevin Keener; Keener and Associates P.C.(57) **CLAIM**

The ornamental design for a chain watch, as shown and described.

DESCRIPTION

FIG. 1 is a top perspective view of a chain watch;
FIG. 2 is a front elevation view thereof;
FIG. 3 is a side elevation view thereof; and,
FIG. 4 is an enlarged sectional view of a link of the chain
watch shown separately for completeness of illustration.
The broken lines shown in the drawings illustrate portions of
the chain watch that form no part of the claimed design.
